CLAIM

The design for a fiber optic connector, as shown and described.

DESCRIPTION

FIG. 1 is a perspective view of a fiber optic connector, showing our new design.

FIG. 2 is a front side elevation view of the fiber optic connector of FIG. 1.

FIG. 3 is a back side elevation view of the fiber optic connector of FIG. 1.

FIG. 4 is a right side elevation view of the fiber optic connector of FIG. 1.

FIG. 5 is a left side elevation view of the fiber optic connector of FIG. 1.

(Continued)

FIG. 6 is a top plan view of the fiber optic connector of FIG. 1; and,
 FIG. 7 is a bottom view of the fiber optic connector of FIG. 1.

The broken line portion of the figure drawings is included to show portions of the article that form no part of the claimed design.

1 Claim, 4 Drawing Sheets
